PRINTING TELEGRAPH APPARATUS

Carl A. Levin and Carl W. Swan, Chicago, Ill., assignors to Teletype Corporation, Chicago, Ill., a corporation of Delaware

Application September 20, 1941, Serial No. 411,658

12 Claims. (Cl. 178—29)

This invention relates to printing telegraph apparatus and more particularly to page printing type wheel telegraphic recorders.

The principal object of the invention is the provision in a type wheel recorder of a simple mechanism which effects selection of functional instrumentalities for operation simultaneously with the selective setting of the type wheel selecting mechanism.

The invention features an apparatus in which the setting of type wheel controlling code discs is effected by a selector which simultaneously effects the setting of code bars which control the selection of function mechanisms.

In accordance with one embodiment of the invention as applied to telegraph printers of the general type disclosed in the copending application of Albert H. Reiber, Serial No. 77,796 filed May 4, 1936, and Patent No. 2,247,403 issued to Albert H. Reiber, July 1, 1941, the transfer bell cranks which are selectively set in response to the received signals thereby to set the notched code discs for selecting type for actuation, also set a series of code bars which control the selection of function levers for actuation. In the structure of the present invention, only one cam shaft is provided as in the structure of Reiber application Serial No. 77,796, but the last character of a message is printed without the necessity of utilizing an idle cycle of the apparatus, and no characters are stored in the printing portion of the apparatus. In the present structure there are provided printing bail and function bail controlled mechanisms. These two bails are set for operation by cams on the single cam shaft and are spring actuated substantially simultaneously at the end of the cycle of the cam shaft. It is unnecessary with this structure to leave the last character stored or to provide an extra cam shaft for performing the printing, line spacing and other functions, due to the fact that the functions are selected simultaneously with the setting up of the type wheel to select characters to be printed. The function selecting mechanism comprises, in addition to the settable code bars set under control of the bell cranks which also selectively set the type selecting code discs, a series of function controlling levers urged into the notches in the settable code bars and normally held out of the notches in the code bars by a function restoring member which at a predetermined time in the cycle of operation of the apparatus releases the function controlling levers and permits any one of them which is in alignment with aligned notches in the code bars to

fall into the code bars, thereby to permit the function levers to select one or the other of the function arms for operation. There are seven of the function controlling levers provided and they are normally spring-biased for selection by the code bars. These function controlling levers are the line feed lever, blank function lever, bell function lever, carriage return lever, figures or shift lever, letters or unshift lever, and unshift on space function lever, and the levers control the performance of the various functions as indicated by their names. Upon the selection of any one of the line feed, bell or break lock functions for operation by the function controlling levers, the particular function to be performed will be effected by its function bar under the control of the function bail cam, which as pointed out hereinbefore, operates simultaneously with the printing cam at the end of the cycle of operation and which normally tends to move all of the function bars to operating or operative position.

In the herein disclosed embodiment of the present invention there is provided a type wheel arresting mechanism which includes a type wheel elevating cam for actuating a type wheel elevating bell crank, one arm of which is connected to the plunger of a dashpot, and the other arm of which is connected to a camming rod for lifting a type wheel supporting frame a predetermined amount with respect to a frame guide in each signal receiving cycle of the apparatus. The carriage supporting frame and frame guide are movable as a unit upon the receipt of a shift or figures code signal, and unshift or letters code signal, thereby to select a row of type on the type wheel for printing in upper or lower case characters. In the normal operation of the apparatus, the type wheel will stay in its elevated position so long as code signals are being received by the apparatus at a predetermined rate of speed due to the effect of the dashpot on the type wheel lifting bail in resisting the type wheel elevating bell crank in its movement toward normal position. However, upon cessation of message reception by the apparatus or when there is a slight pause in the transmission of signals, the type wheel lifting bail spring will move the cam roller on the type wheel lifting bell crank into engagement with the low portion of the type wheel lifting bail cam, thereby to render the last line of printed material visible. Some of the features disclosed but not claimed herein are claimed in the copending application of Carl A. Levin, Serial No. 411,659, filed Sept. 20, 1941.

A better understanding of the invention may be had by reference to the following detailed description when considered in conjunction with the accompanying drawings, wherein:

Fig. 1 is a front elevational view of apparatus embodying the invention;

Fig. 2 is a side elevational view of the apparatus shown in Fig. 1;

Fig. 3 is a fragmentary view in perspective of the apparatus shown in Figs. 1 and 2, showing some of the details of the invention;

Fig. 4 is a fragmentary plan sectional view taken along the line 4—4 of Fig. 1;

Fig. 5 is a fragmentary plan sectional view taken along the line 5—5 of Fig. 2;

Fig. 6 is a fragmentary sectional plan view on an enlarged scale, taken along the line 6—6 of Fig. 2;

Fig. 7 is a detail sectional view taken along the line 7—7 of Fig. 6;

Fig. 8 is a fragmentary sectional view taken along the line 8—8 of Fig. 6;

Fig. 9 is an enlarged fragmentary sectional view taken on the line 9—9 of Fig. 2; and

Fig. 10 is a fragmentary sectional plan view taken on the line 10—10 of Fig. 2.

Referring to the drawings wherein like reference characters designate the same parts throughout the several views, particular reference is first had to Figs. 1 and 2 where, in front and side elevation, there are shown portions of a base or framework member 11 parts of which have been broken away to conserve space. The details of the base or framework member 11 have not been completely shown since this portion of the apparatus is substantially the same as that shown in Patent No. 2,247,408, granted July 1, 1941, to Albert H. Reiber. Similarly, the specific details of the keyboard mechanism (not shown) and the details of the distributor 12 which is shown herein need not be described fully in this application since they are of exactly the same construction as in Reiber Patent No. 2,247,408. As in said patent, a motor 13 is suitably mounted upon the base or framework 11 and supplies power for driving the various parts of the apparatus through its driven shaft 14, Fig. 4.

The shaft 14 has fixed to it a driving gear 15 which meshes with a type wheel shaft gear 16 and a cam shaft gear 17. The distributor 12 is driven from the cam shaft gear 17 through an intermediate distributor driving gear 18 (Fig. 1), mounted on a shaft 19, the lower end of which carries a worm gear 20 which in turn meshes with a gear 21 (Fig. 2) on a distributor shaft 22.

The type wheel shaft gear 16 is mounted on a type wheel shaft 23 which has a type wheel 24 slidably keyed to it. The type wheel and type wheel shaft are normally urged to rotate by frictional clutch mechanisms not shown herein, but shown in detail in Reiber Patent No. 2,247,408 to present the type pallets in the type wheel selectively into association with a platen 25, where they may be actuated by a print hammer 26. The platen 25, its carriage designated generally by the numeral 27, and the code discs for selectively stopping the type wheel at selected positions are the same as in the afore-mentioned copending application and patent of Albert H. Reiber.

The selector mechanism, as shown generally in the various figures and as designated by the reference numeral 30, is of the same construction as that shown in the Reiber application and patent mentioned hereinbefore and need not be described in detail herein. It suffices to state that

the selector mechanism is mounted on the main shaft 31 which also supports the main or cam shaft drive gear 17, the gear 17 being fixed to the shaft 31, and the selector mechanism being frictionally urged to rotate with the shaft 31. In the present embodiment of the invention a single cam shaft is provided as in said copending application Serial No. 77,796 and upon the receipt of a starting impulse in the selector mechanism 30 and initiation of operation thereof, the clutch throw-out lever 32 (Fig. 1) will be removed from engagement with driven clutch sleeve 33 and will permit a spring 34 to force the sleeve 33 into engagement with a driving sleeve 35 keyed to the shaft 31. The driven clutch sleeve 33 is keyed to and drives a main clutch shaft sleeve 36 on which are mounted on a selector transfer cam 37, a function bail cam 38, and a type wheel lifting bail cam 39, together with a printing bail cam 40 (Fig. 1). The cams 31, 38, 39, and 40 on the sleeve 36 have associated with them mechanisms for effecting the functional operations under the control of the cams.

The selection for operation of the various functional mechanisms is under the direct control of the selector mechanism 30. In the present apparatus the selection of type pallets on the type wheel 24 for cooperation with the print hammer 26 is effected in exactly the same manner as in the said copending application and patent of Albert H. Reiber referred to hereinbefore; that is, as more clearly shown in Fig. 5, a series of swords 41 are set under the joint control of a selector shaft and electromagnet (not shown herein but clearly illustrated in the said copending application and patent to Albert H. Reiber) for controlling the setting of transfer levers 42. Associated with the transfer levers 42 are a series of code disc levers 43, one for each of the transfer levers and similar to but not exactly the same as those shown in said copending application and patent. In the said copending application and patent, the code disc levers are simple bell crank levers, but in the present invention the code disc levers each have an additional arm 45 formed on them having a rounded tip 46 which extends into a slot 47 in a code bar 48 associated with each of the code disc levers 43. The transfer levers 42 are pivoted on pivot studs 49 and receive the extending arm of the code disc levers 43 in their bifurcated ends, as shown most clearly in Fig. 5, whereas the levers 43 are pivoted on a pin or shaft 50, whereby the positioning of the transfer levers 42 will effect a setting of the code disc levers 43 thereby to set the code discs 44 and select type pallets in the type wheel 24 for actuation when a character is to be printed. Similarly, the setting of the code disc levers 43 will effect a setting of the code bars 48 which are spaced apart by spacer members 51 (Fig. 2) and are slidable on posts 52 and 53 extending upwardly from a plate 54. The edges of the code bars 48 opposite to the slots 47 are notched to select permutatively any one of seven function controlling bars 55 to 61, inclusive, by permitting a selected bar to fall into aligned notches in the code bars 48 under the urging of its biasing spring, one of which is provided for each of the function controlling bars 55 to 61. The function controlling bars 55 to 61, are pivoted on a pivot rod 62 mounted on a stationary plate 63, bent over portions 64 and 65 of which support the pivot rod 62. The function controlling bars 55 to 61 control the functions of line feed, blank, bell, carriage return, figures or shift, letters or unshift, and unshift on space, respec-

tively. The mechanism cooperating with the function controlling bars will be described hereinafter together with their operation in the order just named.

Upon the receipt, in the selector mechanism 30, of a line feed signal code combination, the line feed function controlling bar 55 will be permitted to drop into aligned notches in the code bars 48 under the influence of its biasing spring which urges it to rock counterclockwise, as viewed in Fig. 1. Cooperating with the function controlling bar 55 is a line feed bar 70 which together with a bell bar 71 and a break-lock bar 72 are pivoted on a post 73 (Fig. 3) fixed to a function bail 74. The bars 70, 71, and 72 are suitably spaced on the post 73 which also carries a spacing bar 75 and a resetting bar 76. The function bail 74, which carries the post 73 on its two parallel arms, is pivoted on a function bail pivot 71 and carries a cam roller 78 on its forwardly extending arm, which cam roller is in engagement with the function bail cam 38. The bars 70, 71, and 72, as most clearly shown in Figs. 3 and 4, are bifurcated to provide two rearwardly extending arms, one of which extends into the path of projections 79, 80, and 81 (Fig. 9) on the function controlling bars 55, 56 and 57, respectively. It should be noted that the arm of bar 70 is in alignment with the projection 79, that the arm of bar 71 is in alignment with the projection 81, and that the arm of bar 72 is in alignment with projection 80. The bars 70, 71, and 72 are normally urged to rock in a counterclockwise direction, as viewed in Fig. 3, under the influence of their biasing springs 82, 83, and 84, respectively, which are connected to the forwardly extending portions of the bars 70, 71, and 72, respectively, and are fixed to a post 85 extending upwardly from the lowermost one of the two parallel arms of bail 74. The biasing springs 82, 83, and 84 attempt to draw the post 85 and the outer ends of the bars 70, 71, and 72 together, thereby serving two purposes; that is, the springs attempt to rock the bars 70, 71, and 72 counterclockwise (as viewed in Fig. 3) about the post 73, and since said bars are blocked by the projections 79, 80, and 81 on the function controlling bars 55, 56, and 57, the springs 82, 83, and 84 will tend to hold the cam roller 78 in engagement with the cam surface of the cam 38. However, whenever one of the function controlling bars 55, 56, or 57 is permitted to rock counterclockwise as viewed in Fig. 1 about the pivot rod 62, its projection 79, 80 or 81 will rock the line feed bar 70, bell bar 71, or break-lock bar 72 against the action of its associated spring 82, 83, or 84, thereby to move the rear end of the select bar 70, 71, or 72 into position to actuate its associated function mechanism.

Positioned adjacent the rear of the machine are three function levers 87, 88, and 89 associated with the line feed, blank, and bell functions and having shoulders 90, 91, and 92 (Fig. 10) respectively, formed thereon for engagement by the line feed bar 70, break lock bar 72, or bell bar 71, respectively, whichever bar 70, 71, or 72 has been selected for operation. If it be assumed that the line feed bar 70 has been selected for operation by the proper positioning of the code bars 48, bar 70 will be permitted to rock to the clockwise position (as viewed in Fig. 10) thereof under the influence of the function controlling bar 55 which will move its projection 79, against the arm of the line feed bar 70 and move it against the action of its biasing spring 82, thereby to carry the rear end of the

long arm of the bar 70 into the path of the shoulder 90 of function lever 87. As the function bail cam 38 rocks function bail 74 in a counterclockwise direction, the entire assembly 5 of the bail 74 and the function bars 70, 71, 72, 75, and 76 will be moved bodily toward the rear of the machine, and when the line feed bar 70 has been rocked clockwise with respect to the bars 71 and 72, its rear end will engage the shoulder 90 on line feed function lever 87 to rock the function lever 87 in a counterclockwise direction about a post 93 which supports it and the function levers 88 and 89. The function lever 87 is articulated to a link 94 which is in turn connected to a line feed bail 95. The line feed bail 95 is pivoted on the framework at 96 and has an upper portion which is always in the path of a roller 97 mounted on the lower end of a pawl actuating lever 98 fixed to a shaft 99 which in turn has a pawl actuating arm 100 fixed to it. The pawl actuating arm 100 has a pawl 101 pivoted at its upper end and normally urged into engagement with a line feed ratchet 102 connected to the platen 25 for effecting line feeding operations as described more in detail in the patent granted to Albert H. Reiber, No. 2,247,408.

If a blank signal, that is, a signal of five spacing impulses, is received by the apparatus, the function controlling bar 56 will be permitted to drop into aligned notches in the code bars 48 and in so doing will move its projection 80 against the break lock bar 72 thereby to move the rear end of the break lock bar 72 into alignment with the shoulder 92 on function lever 89, whereby 30 when the function bail 74 is rocked to its ultimate counterclockwise position the break lock bar 72 will rock function lever 89 about the post 93 to close a pair of contacts not shown, but associated with the function lever 89 and perform the break lock function as described more 35 in detail in the patent granted to Albert H. Reiber, No. 2,247,408.

If the function controlling bar 57 is selected by the code bars 48 presenting aligned notches 45 for receiving the function controlling bar 57 due to the receipt by the selector mechanism of a signal representing the character "S" and comprising marking impulses in the first and third impulse periods and spacing impulses in the 50 third, fourth and fifth impulse periods while the type wheel supporting frame is in upper case position, as will be described more in detail hereinafter, the bell bar 71 will be rocked in a clockwise direction (Figs. 3 and 10) against the action of its biasing spring 83, thereby to carry the rear end of the bell bar 71 into the path of the shoulder 91 on function lever 88, whereby when function bail cam 38 rocks function bail 74 in a counterclockwise direction (Figs. 3 and 4) the rear end of the bar 71 will engage the shoulder 91 on function lever 88 and move lever 88 counterclockwise (Fig. 10) against the action of its biasing spring 103. When the low portion of 55 function bail cam 38 moves into engagement with the roller 78, spring 83 will restore the bell bar 71 to its normal position and in so doing will permit the biasing spring 103 (Fig. 10) of the bell function lever 88 to snap the bell function lever 88 to its normal position, whereby a weight or clapper 104 on arm 105 of function lever 88 will overtravel slightly and strike the bell 106.

Upon the receipt in the selector mechanism of a carriage return code signal, the code bars 48 will be so set that there will be aligned notches 70 in them at the point where they are engaged

by the carriage return function controlling bar 58. The function controlling bar 58 will thus be allowed to fall into the aligned notches under the action of its biasing spring and in so doing will be permitted to rock in a counterclockwise direction, as viewed in Fig. 1. The function controlling bar 58 for carriage return has a laterally extending portion 116 (Fig. 4) which terminates in an upwardly extending projection 117, Figs. 4 and 6. The projection 117 enters into a slot 118 in a link 119 which is in turn articulated to a lever 120 pivoted at 110 and having a rounded formation at its free end for engagement with a trip lever 121. Trip lever 121 is pivoted on a pivot stud 122 and is normally urged to rock in a clockwise direction (Fig. 4) by a contractile spring 123 connected to the trip lever 121 and a latching lever 124. The trip lever 121 is provided with a cam surface 125 bearing against a projection 126 on a pawl supporting member 127 which carries adjustably fixed thereto a pawl 128 and which is normally urged to rotate in a counterclockwise direction by a biasing spring 129. When the projection 117 on the carriage return controlling bar 58 is moved to the right as viewed in Fig. 4, the link 119 will impart movement in a clockwise direction to the lever 120, thereby to rock the trip lever in a counterclockwise direction and move the camming surface 125 thereof to the left, Fig. 4, to rock latching pawl 128 out of engagement with the spacing ratchet 130. The spacing ratchet 130 is fixed on a carriage feeding shaft 131 which drives the carriage in exactly the same manner as the carriage is driven in the structure of the copending application.

The rear end of lever 121 has a shoulder 132 formed thereon which will be engaged with the latching lever 124 when trip lever 121 is rocked in a counterclockwise direction, Fig. 4, spring 123 opposing the counterclockwise movement of lever 121 and causing lever 124 to rock clockwise sufficiently to engage its left end, Fig. 4, with the shoulder 132. The retaining pawl 128 will be locked out of engagement with the ratchet 130 each time the carriage return function selecting bar 58 is selected by the code bars 48 due to the engagement of the left end, Fig. 4, of the latching lever 124 with the shoulder 132 on lever 121, until lever 124 is rocked in a counterclockwise direction against the action of its biasing spring 123, as will be described more in detail hereinafter.

The right side of the lever 121 as viewed in Fig. 4, also constitutes a cam surface for engaging a pin 139 fixed in the spacing bar 75 to hold a pawl portion 133 of the spacing bar 75 out of engagement with the teeth of the ratchet 130 whenever the carriage return function has been performed. It should be noted at this time that the bar 75 is normally urged into a position where the pawl portion 133 thereof will engage the teeth of the ratchet 130 by a spring 134 so that in normal operation of the apparatus the spacing function will take place for each cycle of the apparatus. It should also be noted that the spacing bar 75 is not positively driven by the function bail 74 but is permissively driven due to the construction of the bar 75 as most clearly shown in Fig. 4, wherein the bar 75 has a rectangular opening 135 formed therein in which a spring 136 is positioned, one end of the spring bearing against the end of the opening 135 and the other end of the spring bearing against a collar 137 on the post 73 fixed to the

function bail 74. The spacing bar 75 is provided with an arm designated 75A which extends across in front of the bars 55 to 61 so that if any functional operation is selected for operation in a definite predetermined cycle of the apparatus, the spacing bar 75 will be rocked clockwise about the post 73 to prevent the engagement of the pawl portion 133 thereof with the ratchet 130.

In connection with the carriage return and spacing operations which have just been described, it should be noted that there is provided on the post 73 the resetting bar 76 (Figs. 3 and 4) which is invariably operated through the same path each time the function bail 74 is rocked by its associated cam 38. This resetting bar serves to reset the trip latch or latching lever 124 in the cycle of the apparatus following a cycle in which a carriage return function was effected. The bar 76 has an upwardly extending projection 138 formed on it as most clearly shown in Figs. 3 and 4 for cooperation with a resetting mechanism of exactly the same construction as that shown in the afore-mentioned copending application of Albert H. Reiber, Serial No. 77,796.

The figures or shift controlling function bar 59 will be selected for operation by the code bars 48 upon receipt in the selector mechanism of a "figures shift" signal, and when selected in this manner, the "figures" or shift function controlling bar 59 will rock in a clockwise direction, Fig. 1. Pivoted on the rod 62, as most clearly shown in Fig. 7, is a bell crank lever 150 which is biased to rotate in a clockwise direction by its biasing spring 152, and which carries a roller 151 on its substantially vertically extending arm. The roller 151 is held in the path of the function controlling bar 59 and when the function controlling bar 59 is rocked in a counterclockwise direction by its biasing spring due to the alignment of notches in the code bars 48 associated with it, the bell crank 150 will also be rocked in a counterclockwise direction due to the engagement of the roller 151 with the right hand surface, Fig. 7, of the function controlling bar 59.

The bell crank 150 is provided with a shoudered portion 153 which is normally urged over a horizontally extending arm 154 of a case shift lever 155 to restrain the case shift lever 155 from rocking beyond a definite position in a counterclockwise direction as viewed in Fig. 2. The case shift lever 155 is pivoted at 156 on a stationary portion of the frame of the apparatus and is urged to rock in a counterclockwise direction by a spring 157 to carry a projection 158 formed on one of the arms of the lever 155 into engagement with an extension of the function bail cam 74 as shown most clearly in Figs. 2 and 3. The end of the spring 157 opposite to that secured to the case shift lever 155 is secured to a pin 159 extending horizontally from a ribbon feeding lever 160. The ribbon feeding lever 160 is provided with a downwardly projecting extension 161 which engages the one side of the extension on the function bail 74, thus tending to hold the extension 158 and the projection 161 in engagement with opposite sides of the extension on the bail 74, to cause them to follow the movement of the bail 74. However, if the shoulder 153 on the bell crank 150 (Fig. 7) is in the path of the extension 154 on the lever 155, then the lever 155 will not necessarily follow the function bail 74 but the spring 157 will be extended. When, as described hereinbefore, the shoulder 153 is moved out of the path of the extension

154 due to the receipt by the apparatus of a shift function signal the lever 155 will be permitted to rock farther in a counterclockwise direction than it would if the shoulder 153 were in the path of the extension 154 on the lever 155. When the shift function signal is received, the type wheel 24 will be lifted to its maximum height as will be described more in detail hereinafter to print upper case or figures characters, in a manner similar to that described in detail in the Patent No. 2,247,408. A camming projection 182 on the lever 155 is adapted to engage an arm 163 on a case shifting frame 164, which is slidable to either of two positions on a guide pin 165. A pair of shouldered members 166 and 167 also aid in guiding the carriage shifting frame 164, and these members 166 and 167 are fixed in a type wheel supporting frame 168. The type wheel supporting frame 168 is slidable on a pair of posts 169 and 170, similar to the guiding posts for the type wheel supporting frame shown in the copending application of Albert H. Reiber mentioned hereinbefore.

The case shifting frame 164, as most clearly shown in Figs. 1, 2, and 3, is provided with a horizontally extending blocking portion 172 which serves to block the bell function bar 57 from falling into the aligned notches on the code bars 48 upon the receipt of a signal in the selector mechanism representing the letter S in the lower case and "bell" in the upper case. This blocking portion 172, when the case shifting frame 164 has been shifted to its upper position or the "figures" case shift position, will be out of the path of the "bell" function controlling bar 57 and the "bell" function controlling bar 57 will be permitted to drop into the aligned notches in the code bars 48 upon the receipt of a signal representing "bell" or S. It should be noted at this time that the blocking portion 172 of the case shifting frame 164 extends over function controlling bar 56 which controls the blank function, but that the function controlling bar 56 is shorter than the other function controlling bars and therefore will not be blocked from movement into aligned notches in the code bars 48 by the blocking portion 172 in either of its upper or lower positions.

Upon the receipt in the apparatus of a signal representing unshift or "letters" case functions, the code bars 48 will be shifted to a position to present aligned notches to the unshift function controlling bar 60 thereby to permit its biasing spring to rock it counterclockwise, as viewed in Fig. 1. Similarly, upon the receipt of a word-space signal, the "unshift on space" function controlling bar 61 will be permitted to rock in counterclockwise direction, as viewed in Fig. 1, into aligned notches on the code bars 48. Since both of the function controlling bars 60 and 61 control the same function, that is, the unshift function, their operation will be described at the same time.

Pivotedly supported on the rod 62 is a bell crank 180 (Fig. 8) which is positioned between the function controlling bars 60 and 61 and is urged to rotate in a clockwise direction about the pivot rod 62 by a biasing spring 181. The horizontally extending arm of the bell crank lever 180 has a spring 181 connected to it, and the vertically extending arm, as viewed in Figs. 6 and 8, carries a pair of abutments 182 and 183, the abutment 182 extending over into the path of movement of the function controlling bar 60, and the abutment 183 extending over into the

path of movement of the function controlling bar 61, whereby upon the selection of either the function controlling bar 60 or the function controlling bar 61 and its consequent rocking in a counterclockwise direction as viewed in Fig. 1, the bell crank 180 will be rocked in a counterclockwise direction against the action of its biasing spring 181. Thus, the normal position of the bell crank lever 180 is as shown in Fig. 8, to which position the bell crank lever 180 had been moved by the receipt in the apparatus of a spacing or unshift signal, and wherein a lower shoulder 184 is shown engaging a portion 185 of the case shifting frame 164 to hold the case shifting frame 164 from dropping below the position as shown in Fig. 2. A second shoulder 186 is also provided on the bell crank lever 180 for engaging the portion 185 of the case shifting frame 164 when the case shifting frame 164 has been lifted to its uppermost position by engagement of the projection 182 with the arm 163 on the case shifting frame 164 and the release of the horizontally extending arm 154 of lever 155 by the bell crank lever 150. Thus, upon the receipt of a shift or "figures" code signal in the apparatus, and the consequent release of the arm 154 from the shoulder 153, the case shifting frame 164 will be lifted to its uppermost position by the type wheel elevating lever 155 and will be latched in its uppermost position by the bell crank lever 180 whose shoulder 186 will move under the portion 185 of the case shifting frame 164 until an unshift or "letters," or word-space signal is received in the selector mechanism 30. When an unshift signal is received in the selector mechanism 30, bell crank lever 180 will be rocked in a counterclockwise direction as described hereinbefore, and will release the portion 185 of the case shifting frame 164 from the shoulder 186 and permit portion 185 to drop down onto the shoulder 184. As the case shifting frame 164 drops to its lower position, the bell crank 150 will be permitted to block the movement of the lever 155 and prevent it from lifting the case shifting frame to its uppermost position.

As described hereinbefore, the case shifting frame 164 has two positions, and the type wheel supporting frame 168 is movable with respect to the case shifting frame. Fixed to the case shifting frame 164 adjacent its lower end is a roller 187 which is freely rotatable on a post 188 which also supports a guide member 189. The shouldered member 166 is fixed to the type wheel supporting frame 168 and carries a roller 190. A camming member 191 is guided between the guide member 189 and the case shifting frame 164 and is engaged between the rollers 188 and 190. Camming member 191 is loosely articulated on the free end of a type wheel elevating cam lever 192 pivotally supported by the function bail pivot post 71 and biased to rock in a clockwise direction by biasing spring 193 (Fig. 3). Cam lever 192 carries a cam roller 194 intermediate the ends of its forwardly extending arm 195. The arm 195 of lever 192 under the influence of spring 193 normally tends to hold the cam roller 194 in engagement with type wheel lifting bail 39, and arm 195 is slotted as shown at 196 to engage or receive a plunger actuating disc 197 fixed to a piston rod or a plunger rod 198 (Figs. 3 and 4). The plunger rod 198 has fixed to its left end, as viewed in Fig. 4, a piston member 199 which is freely movable to the right in a dashpot cylinder 200. The

dashpot cylinder 200 is provided with an adjustable escape valve designated 201, whereby the rate of travel of the piston 199 and consequently the rate of travel of the type wheel elevating cam lever under the urging of spring 193 may be regulated. The type wheel elevating cam lever 192 is operated by its cam once for each cycle of the apparatus to raise the type wheel to either one of its printing positions depending upon the case in which the case shifting frame 164 happens to be positioned. The valve 201, however, may be adjusted to so regulate the speed of movement of the piston 200 that the camming member 191 will not be completely retracted to its normal position by spring 193 to permit the type wheel to drop down and render visible the last character printed if a message is being received at normal speed. If the valve 201 is properly regulated to retard the return of the piston 199, the receipt of signals at an average rate of speed will result in the cam 39 imparting a slight degree of oscillation to its associated cam lever 192 but the cam member 191 will not return to its normal position as shown in Figs. 2 and 3, but will remain in a position where the wider portion thereof is between the rollers 187 and 190. Type wheel supporting frame 168 will stay in its upper position with its type pallets in alignment with the print hammer while the cam member 191 moves back and forth a short distance, the wide portion of the cam member 191 remaining between the two rollers 187 and 190. However, if there is an appreciable pause or interval between the receipt of two signals by the selector mechanism 30, the cam roller 194 will be permitted to move to the low point of cam 39 and the type wheel 24 will be permitted to move down out of the position in alignment with the platen 25 due to the retraction of the cam member 191 to its normal position and the consequent movement of the narrow end portion of the camming member 191 into a position between the rollers 187 and 190.

The print hammer 26 provided herein, is of exactly the same construction as that provided in the apparatus disclosed in detail in Patent No. 2,247,408, and is driven by a printing bail a sufficient distance so that its own inertia will cause it to overtravel and effect printing as described in detail in said copending application. However, the printing bail 205 is driven by a printing cam lever 206 carrying a cam roller 207 in engagement with printing bail cam 40. In the present apparatus, the printing bail cam is mounted upon the main clutch shaft sleeve 36 and is so cut that printing takes place just prior to the end of the cycle of the cam sleeve and substantially simultaneously with the return to normal of the function bail 74 and the type wheel elevating cam lever 192.

In the operation of the apparatus, the selection of characters for printing is thus performed under control of the selector mechanism 30 in the same manner as in the copending application of Albert H. Reiber identified hereinbefore. However, the selection of functions for operation in the herein described structure is performed simultaneously with the setting of the code discs which control the rotational position of the type wheel 24 by setting the function controlling bars 55 to 61 singly and performing the selected function in the same cycle that the selection is made.

After any function or character printing operation has been performed it is necessary to restore the apparatus to normal so that a succeed-

ing operation may be performed. Since, in the present apparatus, printing and functional operations take place in the same cycle with their selection, the restoration of the apparatus to normal occurs in the first part of each cycle under control of the selector transfer cam 31.

Associated with cam 31 (Fig. 4) is a cam roller 210 rotatably mounted on one arm of a transfer bail lever 211 to which a spring biased transfer bail 212 is adjustably secured. Lever 211 has articulated to it a cam lever 213 provided with cam surfaces 214 and 215. The cam surface 215 engages a roller 216 and when the transfer bail 212 unlocks the transfer levers, as described in said copending application of Albert H. Reiber, cam lever 213 will be drawn toward the front of the machine and will be rocked counterclockwise due to its engagement with the roller 216. As cam lever 213 rocks counterclockwise, cam surface 215 thereon will move along a roller 219 fixed to a restoring lever 217 and will rock restoring lever 217 counterclockwise (Fig. 4) about pivot pin 218. The left edge (Fig. 4) of lever 217 extends across function controlling bars 55 to 61 inclusive, and will restore them to normal at the beginning of each cycle thereby to restore code bars 48 and prepare them for receiving the next signal.

While a specific embodiment of the invention has been described hereinbefore, it will be understood that various modifications and adaptations thereon may be made without departing from the scope of the appended claims.

What is claimed is:

1. In a printing telegraph apparatus, a type wheel, code discs for controlling the selective positioning of said type wheel, a selector mechanism, levers settable under control of the selector mechanism for moving said code discs, function controlling mechanisms, and means under control of said levers for controlling the operation of said function controlling mechanisms.

2. In a printing telegraph apparatus, a type wheel, code discs for controlling the selective positioning of said type wheel, a selector mechanism, levers settable under control of the selector mechanism for moving said code discs, function controlling mechanisms, and code bars set by said levers for controlling the operation of said function controlling mechanisms.

3. In a printing telegraph apparatus, a type wheel, code discs for controlling the selective positioning of said type wheel, a selector mechanism, levers settable under control of the selector mechanism for moving said code discs, code bars actuated by said levers, function mechanisms, and function controlling members selectable by said code bars for controlling the operation of said function mechanisms.

4. In a printing telegraph apparatus, a type wheel, a selector mechanism responsive to received signals for selectively controlling the setting of said type wheel, a shaft for driving said selector mechanism, a cam sleeve on said shaft, function mechanisms driven by said cam sleeve, and function controlling means directly controlled by said selector mechanism simultaneously with the control of the type wheel thereby for controlling effectiveness of the function mechanisms.

5. In a printing telegraph apparatus, a function bail, means for actuating said bail in each cycle of the apparatus, function mechanisms selectively operable by said bail, a secondary selector for controlling the effectiveness of said

function mechanism, a type wheel selectively settable in each cycle of the apparatus, an additional secondary selector for said type wheel, and a signal responsive selector for directly and simultaneously controlling the operation of each of said secondary selectors.

6. In a printing telegraph apparatus, a primary signal responsive selector, a type wheel, a secondary selecting mechanism for controlling the position of said type wheel, function mechanisms, an additional secondary selector mechanism for controlling said function mechanisms, and transfer means for directly transferring selections from said primary selector to each of said secondary selector mechanisms.

7. In a printing telegraph apparatus, a primary signal responsive selector, a type wheel, a secondary selecting mechanism for controlling the position of said type wheel, function mechanisms, an additional secondary selector mechanism for controlling said function mechanisms, transfer means for directly transferring selections from said primary selector to each of said secondary selector mechanisms, and a single cam sleeve for controlling said function mechanisms.

8. In a printing telegraph apparatus, a primary signal responsive selector, a type wheel, a secondary selector including a set of code discs for controlling the position of said type wheel, function mechanisms, an additional secondary selector mechanism for controlling said function mechanisms, and transfer means for directly transferring selections from said primary selector to each of said secondary selector mechanisms.

9. In a printing telegraph apparatus, a primary signal responsive selector, a type wheel, a secondary selector including a set of code discs

for controlling the position of said type wheel, function mechanisms, an additional secondary selector mechanism for controlling said function mechanisms, transfer means for directly transferring selections from said primary selector to each of said secondary selector mechanisms, and a single cam sleeve for controlling said function mechanisms.

10. In a printing telegraph apparatus, a signal responsive selector, a type wheel, a set of code discs for controlling the position of said type wheel, function mechanisms, a set of bars for controlling said function mechanisms, and transfer means for simultaneously and directly transferring selections from said selector to said code discs and said bars.

11. In a printing telegraph apparatus, a primary signal responsive selector, a printing mechanism, a secondary selector for controlling the operation of said printing mechanism including character selection, function mechanisms, an additional secondary selector for controlling said function mechanisms, and transfer means for simultaneously and directly transferring selections from said primary selector to each of said secondary selectors.

12. In a printing telegraph apparatus, a primary signal responsive selector, a type wheel, a secondary selector for controlling the position of said type wheel, a series of selectable bars for performing function operations, an additional secondary selector for selecting said bars, and transfer means for directly transferring selections from said primary selector to each of said secondary selectors.

CARL A. LEVIN.
